UNITED STATES PATENT OFFICE.

FREDERICK L. WEEMAN, OF PORTLAND, MAINE.

OIL-BURNER.

1,078,475.

Specification of Letters Patent. Patented Nov. 11, 1913.

Application filed April 25, 1913. Serial No. 763,583.

To all whom it may concern:

Be it known that I, FREDERICK L. WEE-
MAN, a citizen of the United States, residing
at Portland, in the county of Cumberland
5 and State of Maine, have invented a new
and useful Oil-Burner, of which the follow-
ing is a specification.

This invention has reference to improve-
ments in oil burners, and its object is to
10 provide a simple form of oil burner which
will produce complete vaporization and com-
bustion of the oil without soot and with the
production of an intense heat.

The invention comprises the casting de-
15 signed to be placed in the fire box of a stove
and may replace the grate, and carried by
this casting are burner heads fed by pip-
ing through which the oil flows to the burner
20 heads and during which flow the oil may be
preheated, while the air supply may be regu-
lated by the usual draft appliances with
which stoves are customarily provided.

The invention also includes a lighting de-
vice which may form a practically perma-
25 nent part of the structure without interfer-
ence with the burner heads and yet read-
ily be moved into operative relation to the
burner heads.

The invention will be best understood
30 from a consideration of the following de-
tailed description, taken in connection with
the accompanying drawings forming a part
of this specification, with the further under-
standing that while the drawings show a
35 practical embodiment of the invention, the
latter is not confined to any strict con-
formity with the showing of the drawings
but may be changed and modified so long as
such changes and modifications mark no ma-
40 terial departure from the salient features of
the invention.

In the drawings: Figure 1 is a vertical
front to rear section of the fire box por-
tion of a stove showing the improved burner
45 installed therein, but without any attempt
to show any particular construction of stove.
Fig. 2 is a plan view of the burner removed
from the stove with one of the burner feed
pipes shown in section and the correspond-
50 ing burner head omitted. Fig. 3 is a bottom
plan view of the burner. Fig. 4 is a section
on the line 4—4 of Fig. 2. Fig. 5 is a per-
spective view of a portion of the burner
structure as seen from below.

55 Referring to the drawings there is shown
a stove 1 which may be considered as con-

structed in accordance with ordinary stove
practice, and may represent an ordinary
coal or wood burning stove such as is em-
ployed for cooking, or it may represent a
60 construction of stove designed especially
for the burner of the present invention,
although the latter is adaptable to almost
any ordinary form of cook stove. The stove
1 is shown as provided with the usual upper
65 and lower draft doors 2 and 3, respectively,
the latter opening to that portion of the
stove constituting the ash pit in a coal stove.

There is provided a tray 4 which may be
in the form of a flat casting, having a mar-
70 ginal upturned rim 5 about it and of a size
and shape to practically fill the fire box of
an ordinary stove, resting on the usual ledge
6 of the stove provided for sustaining a
grate, but, of course, there may be other
75 provision for supporting the tray 4.

Through the bottom of the tray there are
provided openings 7 which may be arranged
80 in some symmetrical order, although this is
not at all mandatory, and in the drawings
are shown about one-fourth of the length of
the tray from each end, two such openings
being indicated. Each opening is surround-
ed on what constitutes the upper face of the
tray by a flange 8 spaced from and concen-
85 tric with the opening and leaving a ledge 9
between the opening and the flange. This
ledge is designed to receive feet 10 on the
under side of a cup 11 of an external diam-
eter somewhat less than the internal diam-
90 eter of the flange 8, and the feet 10 are of a
length to bring the lower edge of the cup
11 into such relation to the flange 8 and
opening 7 that air may readily flow through
the opening 7 beneath the cup 11 and around
95 the margins of the same, between the cup
and the flange 8 into the fire chamber of the
stove.

Between each flange 8 and the correspond-
ing end of the tray 4 is a boss 12 and other
like bosses 12 may be formed adjacent the
middle of the tray. Each end boss 12 is
bored and tapped for the reception of a pipe
13 upstanding from the tray and at the
upper end connected by means of an elbow
14 with a laterally extending pipe 15 carry-
ing at the free end a burner head 16 which
latter may be provided with an internal bore
17 in line and communicating with the pipe
15, while leading from the bore 17 are pas-
sages 18 directed downwardly toward the
cup 11 and each terminating in a flaring end
110

19. The arrangement of the parts is such that each burner head 16 is immediately above and appropriately spaced from a respective cup 11 with the passages 18 and 19 directed toward the cup 11 in such manner that any fluid reaching the burner head 16 under suitable pressure will be directed toward the cup 11 and more or less sprayed by the flaring mouths 19 of the passages 18.
- 10 Each pipe 13 is connected by a respective pipe 20 or 21, as the case may be, to a supply pipe 22 which may be common to both pipes 20 and 21, and the latter may each contain a suitable valve 23 by means of which communication between the supply and the respective burners may be controlled or cut off, at will. Each pipe 20 and 21 is connected by suitable fittings to the threaded opening of the respective boss 12.
- 20 At a mid point of the tray 4 near one under side thereof there is formed a boss 24 which may rise from the tray to a greater height than the bosses 12 and pivoted at one end to this boss by a pin 25 is an arm 26 which at the other end is formed into a cup or receptacle 27, and the arm 26 is of such a length that when swung on its pivot pin 25 to one side or the other of a central position it will come directly over a respective cup 11 and directly beneath a respective head 16.
- 25 To protect the parts the tray 4 may be provided with a lining 28 of some refractory material, such as asbestos, and the cups 11 may have a lining 29 of like material, while 30 the cup or receptacle 27 contains a mass of asbestos or some such material which will hold a suitable quantity of oil to be lighted and produce a flame for the preliminary heating of the burner heads 16.
- 35 Let it be assumed that the structure is installed in a stove, and that it is desired to produce a fire, then one of the valves 23 is opened after the cup 27 has been positioned beneath the corresponding head 16 and oil is 40 permitted to flow into the cup until a sufficient quantity has been deposited therein. This oil is now lighted and the flame rising against the head 16 soon heats it to an appropriate heat, after which the priming cup 45 27 may be moved into position beneath the other burner head and the priming operation repeated, while the first head having been sufficiently heated may now supply gasified oil which on being lighted as it 50 issues from the head 16 is directed in the form of a flame toward the cup 11, and meeting air rising through the opening 7 and about the cup 11 produces an intensely hot flame, thereby heating the stove. If one 55 burner is all that is needed, then, of course, the second burner is not preheated and caused to operate, but if both burners are needed, then the preheating operation is repeated as to the second burner, and in a 60 short time both burners may be in operation.

The intensity of the flame may be controlled by the amount of fuel supplied, which is determined by the opening of the valve 23 to the required extent, and also by a suitable manipulation of the draft controlling devices 2 and 3, the draft device 3 providing air supply which will pass about the cup 11 in close relation to the burning oil. The draft device 2 permits a certain degree of cooling by admitting air above the point of greatest combustion.

In the foregoing description the device has been termed an oil burner, but it will be understood that the word oil is used in a more general sense as indicating any fuel adapted to the purpose. It will be observed that the tray 4 forms the bottom of the fire chamber, so that the only air which reaches the fuel from beneath the tray is by way of the passages 7 and spaces about the cup 11 and flanges 8, whereby nicety of control of the air supply is permitted by a manipulation of the ordinary drafts of the stove.

What is claimed is:—

1. An oil burner comprising a basic member having passages therethrough with surrounding upstanding flanges, cups each provided with feet individual thereto and shaped to engage the basic member to support the cup in elevated relation to a respective passage and within the space defined by the flange about said passage, and burner heads in elevated relation to the cups.
2. An oil burner comprising a basic member having passages therethrough with surrounding upstanding flanges, cups supported by the basic member in elevated relation to the passages and within the space defined by the flanges, and burner heads in elevated relation to the cups and provided with supports in the form of conduits rising from the basic member, the burner heads being provided with fuel passages having flaring mouths directed toward the cups.
3. The combination with a stove, of an oil burner tray adapted to be housed in the fire box of the stove and of a size to substantially separate the space above the tray from the space beneath it, said tray having passages therethrough and also provided with flanges in spaced surrounding relation to the passages and upstanding from the tray, pipes upstanding from the tray adjacent the passages and each carrying a burner head in elevated relation to the tray above the respective passage therethrough, and a cup for each passage having feet adapted to rest on the tray within the margin of the respective flange and above the opening through the tray and in position to receive fuel from the burner head.
4. The combination with a stove, of an oil burner tray adapted to be housed in the fire box of the stove and of a size to substantially separate the space above the tray

- from the space beneath it, said tray having 5
passages therethrough and also provided
with flanges in spaced surrounding relation
to the passages and upstanding from the
tray, pipes upstanding from the tray, adjac- 10
ent the passages and each carrying a
burner head in elevated relation to the tray
above the respective passage therethrough,
a cup for each passage having feet adapted
to rest on the tray within the margin of the
respective flange and above the opening
through the tray and in position to receive
fuel from the burner head, and a swinging
arm mounted on the tray and terminating
5 in a cup and having a range of travel to
move beneath either burner head in spaced
relation thereto and in elevated spaced relation
to the corresponding one of the first-
named cups. 15
5. An oil burner provided with a plu-
rality of burner heads, and a lighting mem-
ber intermediately of and lower than the
burner heads, said lighting member com-
prising a receptacle for fuel, and an arm at
25 one end carrying the lighting member and
at the other end provided with a mounting
constructed to permit the movement of the
lighting member to a position beneath and
in operative relation to either of the burner
30 heads, at will. 20
6. An oil burner comprising a tray having
an opening between each end and the center
portion with an upstanding flange sur-
rounding the opening and spaced in con-
centric relation thereto, a cup provided with
35 legs adapted to rest on the tray interior to
each flange and in surrounding relation to
the respective opening, an upstanding duct
adjacent to each opening and carrying a
burner head in elevated relation to a respec- 40
- tive cup with openings in the burner head
directed downwardly toward the cup, and a
lighting member comprising an arm pivoted
to the tray near one side thereof and at the
free end provided with a cup, the arm be- 45
ing of a length to move about its pivotal
support into position beneath either head
and in elevated relation to the correspond-
ing one of the first-named cups. 50
7. A stove provided with a tray in the fire-box of a size to substantially divide the fire box into an upper and a lower chamber, said tray being provided with openings extending therethrough with each opening surrounded by an upstanding flange in 55 spaced concentric relation to the opening, pipes upstanding from the tray in spaced relation to the flanges and each provided with a lateral extension carrying a burner head in elevated relation to the respective 60 opening and having fuel passages directed toward the opening, a cup in elevated relation to each opening and supported by the tray within the margin of the respective flange and beneath the respective burner 65 head, an arm pivoted to the tray near one side thereof and provided at the end remote from the pivot with a cup movable into elevated relation to either of the first-named cups and beneath a respective burner head, 70 and means for supplying fuel to each burner head. 75

In testimony, that I claim the foregoing
as my own, I have hereto affixed my signature
in the presence of two witnesses.
